SHEET-METAL CAR END

1,182,342.

Specification of Letters Patent.

Patented May 9, 1916.

Application filed April 5, 1915. Serial No. 19,409.

To all whom it may concern:

Be it known that we, WILLIAM G. BORN, a subject of the Emperor of Germany, and JAMES L. LANE, a citizen of the United States, both residing at Chicago, in the county of Cook and State of Illinois, have invented certain new and useful Improvements in Sheet-Metal Car Ends, of which the following is a specification.

10 Sheet-metal end-walls for railway box-cars with various styles and forms of stiffening and strengthening corrugations or embossments have been proposed and used to some extent.

15 Our invention relates in general to such metal car-ends, its main and leading objects being the provision of a sheet-metal end-wall possessing a maximum degree of strength with a minimum amount of plate deformation, and one with relatively long, sweeping curves which may be easily pressed, rather than one with comparatively sharp or abrupt changes in shape or configuration.

20 A further feature of the invention is the use of such a design and shape that the metal during its pressing or deformation will not be materially stretched, that is to say, will retain nearly or substantially its original thickness throughout.

25 Another object of the invention is the formation of the plate into such a shape that its strength will be substantially uniform throughout, but with, however, its point of greatest resistance to deflection below the center of the car-body end. By avoiding sudden and abrupt changes in the shape of the metal, that is, by employing sweeping curves or gradual changes in connection with the 30 corrugations, there is less tendency for the plate to retain water, thereby discouraging or reducing the formation of ice.

35 In order that those skilled in this art may have a full and complete understanding of the invention, we have illustrated a preferred embodiment of the same in the accompanying drawing which forms a part of this specification, and throughout the various views of which, like reference characters refer to the same parts.

40 In the drawing: Figure 1 is a face view of the novel and improved form of sheet-metal car-end; Fig. 2 is a vertical cross-section on line 2--2 of Fig. 1; Fig. 3 is a horizontal cross-section on line 3--3 of Fig.

1; and Fig. 4 is a diagonal cross-section on line 4--4 of Fig. 1.

45 Railway-car end-walls are ordinarily slightly higher than they are wide, and the center of pressure of a load is ordinarily 60 below the geometrical center of such an end-wall. It is desirable therefore that the point of greatest strength of a sheet-metal plate used for such a car-end should be at approximately the point of greatest strain or 65 load. A load, such as grain, for instance, constantly exerts an outward pressure on such a plate-wall, but, of course, such a normal strain is greatly increased due to the sudden stopping and starting of the train, 70 and other conditions which tend to shift the load longitudinally of the car-body.

75 Although it has been stated that the point of greatest strength is below the geometrical center of the plate, it is, nevertheless, to be borne in mind that one of the objects of the invention is to so emboss or corrugate the plate whereby it will possess substantially uniform strength throughout, although this ideal condition could ordinarily 80 be only approximated in actual practice.

85 In the preferred incorporation of the invention, as illustrated in the drawing, the originally flat metal-plate 10 is pressed or shaped with suitable dies to provide a relatively large round boss 11 with its center below the center of the plate for the reason indicated. The boss is somewhat convex, as at 12, and its edge 13 is of somewhat general conical formation, and merges into a conical portion 14 of relatively slight taper. Experience has indicated that in pressed-metal structures of this general character, 90 in order to secure the greatest degree of strength, a comparatively definite or fixed relation must exist between the height or depth of the boss and its circumference. The depth to which the boss may be pressed out of the plane of the original sheet is limited 95 by the nature of the structure of the car and the standards adopted by car builders, and, consequently, the size or diameter of the boss is determined by such depth. The boss is further strengthened and reinforced 100 by the use of the gradually sloping conical connection 14 with the part of the plate remaining in the original plane.

105 As is illustrated, the four corners of the plate are each provided with a pressed boss 110 of general triangular shape of less depth

than the central circular boss. At the bottom of the plate, the two triangular bosses or reinforcements 15 and 16 are entirely separate from one another, but at the upper portion of the plate, owing to the greater space present, the two corresponding parts 17 and 18 are united above the boss 11, forming a continuous strengthening rib of the shape illustrated.

10 It should be observed that there are no abrupt or sudden changes in the shape of the metal, and, consequently, no material stretching of it with a resulting reduction in thickness. In other words, a maximum 15 of strength is secured by the design proposed, by deforming in the manner indicated, with a minimum reduction in its gage thickness. Stated differently, the central boss is so designed as to greatly strengthen 20 the plate, and such stiffening is reinforced by the smaller supplemental bosses or deformations at the corners of the plate.

To those skilled in this art, it will be apparent that various minor mechanical 25 changes may be made in the structure herein set forth without departure from the substance or essence of the invention and without the sacrifice of any of its substantial benefits and advantages.

30 We claim:

1. An embossed sheet-metal car-end plate of the character described of general rectangular shape having an outer marginal portion constituting the plane of the plate, 35 a substantially-central relatively-large boss, and an intermediate cone section of relatively less height than said boss, extending outwardly from the base of the boss and merging into said marginal portion, substantially as described.

2. An embossed sheet-metal car-end plate of the character described of general rec-

tangular shape having an outer marginal portion constituting the plane of the plate, a substantially-central relatively-large boss, 45 and an intermediate cone section of relatively less height than said boss extending outwardly from the base of the boss and merging into said marginal portion, the plate also having a plurality of bosses of 50 general triangular form at its corner portions, substantially as described.

3. An embossed sheet-metal car-end plate of the character described of general rectangular shape having an outer marginal 55 portion constituting the plane of the plate, a substantially-central relatively-large boss a cone section of relatively less height than the boss extending outwardly from the base of the latter and merging into said marginal portion, and a plurality of bosses of 60 general triangular form at the corner portions of the plate, the two upper of said triangular bosses being united above the main boss, substantially as described. 65

4. An embossed sheet-metal car-end plate of the character described of general rectangular shape having an outer marginal portion constituting the plane of the plate, a relatively-large round boss whose center is 70 below the geometrical center of the plate, and an intermediate cone section of relatively less height than the boss extending outwardly from the base of the latter and merging into the said marginal portion, the 75 corner portions of the plate having bosses of general triangular form, substantially as described.
